UNITED STATES PATENT OFFICE.

EDWARD J. THURBER, OF NEW ORLEANS, LOUISIANA, ASSIGNOR TO THURBER, PERKINS AND COOK, INCORPORATED, OF NEW ORLEANS, LOUISIANA, A CORPORATION OF LOUISIANA.

FASTENING MEANS FOR CURTAINS.

Application filed July 29, 1924. Serial No. 728,929.

To all whom it may concern:

Be it known that I, EDWARD J. THURBER, a citizen of the United States, residing at New Orleans, parish of Orleans, and State of Louisiana, have invented certain new and useful Improvements in Fastening Means for Curtains, of which the following is a specification.

This invention relates to curtain fasteners particularly adapted to use in connection with curtains having overlapping edge portions. The improved fasteners are intended for use with any form of curtain mounting, or with a curtain that may engage a roller and be stored in the vehicle top, or with a curtain of ordinary form, but in all uses of the improved devices the adjacent edges of the curtains are overlapped and positively held in this position by the fasteners. The primary object of the invention is to provide a fastener that will bring the edges of the curtains together and hold them in overlapped association, and also stiffen the curtain structure at the overlapped portions thereof.

With a roller form of curtain the fasteners commonly used are objectionable and do not easily wind, or when they are wound injure the fabric of the curtain, and therefore such common form of fastener is not commercially practicable on roller curtains. It is preferred that the present improvement be used in connection with curtains attached to rollers disposed to always insure an overlapped association of the edge portions of the curtains and permit the same to easily wind and unwind relatively to the rollers without injury to the fabric of the curtains.

With the foregoing and other objects and advantages in view, the invention consists in the construction and arrangement of the several parts which will be more fully hereinafter described and claimed.

In the drawings:

Fig. 1 is a side elevation of a portion of a vehicle body and a top curtain roller structure broken through in parts and the top shown in dotted lines and having the improved curtain fastener applied thereto and illustrated in operative position in full lines and in positions of disuse in dotted lines.

Fig. 2 is a transverse vertical section on the line 2-2, Fig. 1.

Fig. 3 is a transverse vertical section on the line 3-3, Fig. 1.

Fig. 4 is a horizontal section on the line 4-4, Fig. 2.

Fig. 5 is a horizontal section on the line 5-5, Fig. 3.

Fig. 6 is a detail perspective view of one of the improved fasteners shown broken through.

Fig. 7 is a side elevation of a modified form of the fastener illustrated in full and dotted lines and broken through.

Figs. 8 and 9 are sections similar to Fig. 2, illustrating the modified form of the fastener in two positions and showing the curtain associated therewith.

Fig. 10 is a section on the line 10, 10, Fig. 7, looking in the direction of the arrow.

The numeral 5 designates a vehicle or automobile body having mounted thereover a top 6, shown in dotted lines, and embodying therein at opposite sides a frame 7 for the curtain assembly and a filler board 8 between the edge 9 of the deck 10 of the top and curtain as shown by Fig. 9. In Figs. 2 and 3 the filler board 8 is illustrated as being mounted between the side bowed ends of the ribs 11 of the top and the curtains. In other words, the filler board extends fully along the inside of each depending side portion of the top and the curtains. The frame 7 for the curtain assembly is made up of frame members having secured thereto at regular intervals bearing brackets 12, which depend therefrom and also extend above the same to operatively receive the spindles 13 of spring rollers 14, the said rollers being arranged in such manner that their extremities will overlap, and the lower rollers as shown by Figs. 2 and 3 are disposed at a greater distance inward from the depending side portions of the vehicle top than the upper rollers, so as to provide for a practical operation of the curtains operatively connected to the said rollers.

This overlapped arrangement of the extremities of the rollers and the means for holding the roller brackets and comprising the frame for this curtain assembly are features well known in my particular form of curtain mountings or installations in connection with automobile tops, and whereby the curtains are always in convenient positions for ready operation by the occupant or occu-

100
105

parts of an automobile or vehicle. The curtain mounting or installation above specified may, however, be modified, but under all changes it is preferred that the curtain-engaging rollers have their extremities overlapped or disposed in such manner that the side edge portions of the curtains will always be retained in overlapped relation, both when the curtains are lowered 10 and also when they are raised.

As hereinbefore indicated, the present improvement consists of fastening means for the overlapped edges of the curtains when the latter are lowered, and the form 15 of the improved fastener as shown by Figs. 1 to 6, inclusive, is in the nature of a flattened S-shaped clip consisting of reversely opening jaw members 16 and 17 having beaded or rolled free edges 18, the jaw 20 members being continuous through the medium of curved bends 19. Each clip is long enough to extend downwardly from the top structure or from the curtain assembly and the filler board to the upper portions 25 of the opposite sides of the vehicle or automobile body. Each clip is preferably constructed of resilient material such as metal and may be suitably treated to resist oxidation. Both jaws 16 and 17 are continuous 30 through the bends 19 with an intermediate flat body member 20, which is extended at its upper end to form an intermediate guard or guide partition 21. The jaw 16 is located at the inner side of the 35 clip and has a lower depending attaching terminal 22 with an opening 23 there-through, and at its upper extremity the same jaw has an upwardly projecting fulcrum arm 24, which terminates above the upper edge of the guide or partition 21 and has an opening 25 in the upper terminal 40 thereof. The fulcrum arm is pivotally connected to a fulcrum plate 26 secured to the lower outer portion of the frame 7 for the curtain assembly, and whereby the clip may 45 be swung laterally when not in use upwardly into the top and be engaged by a hook or analogous device 27 depending from an upper part of the frame 7, as clearly 50 shown by Fig. 1 which illustrates all of the clips in dotted positions stored within the top. The lower attaching terminal or extremity 22 of the clip is removably attached to the outer side of the upper portion 55 of the vehicle or automobile body by a screw 28. Each clip is similarly mounted and has like operation, and in addition to reliably holding the overlapped edges of the curtains 15, these clips also serve as 60 reinforcing standards and supports which are primarily intended to rigidly connect the side edges of the curtains and also serve as interposed supporting means between the top and the body of the vehicle. The curtains at their lower edges are provided with

stiffening or reinforcing strips 29, one in each, which operate to expand the jaws 16 and 17 when drawn through the clips so as to render movement of the remaining portions of the curtains through the said jaws relatively easy without objectionable binding or frictional abrasion with relation to the edge portions of the curtains, and when the lower ends of the curtains are pulled through the lower terminals of the 70 jaws as shown by Fig. 3, the lower stiffening or reinforcing strips 29 secured in the curtains will bear as stop means against the lower terminals of the jaws and the latter will then press tightly against and draw the overlapped edge portions of the curtains in close association with the intermediate flat members 20 of the clips. When the curtains are pushed upwardly the rollers 75 14 will regularly take up or wind the curtains, and when the lower edges of the curtains with the strips 29 therein reach an elevated position as shown by Fig. 2, the lower ends of the curtains will always be in convenient position for ready engagement by the occupants of a vehicle or automobile for drawing the same downwardly when desired. The improved curtain edge fasteners or clips when not in use and stored or turned upwardly into the top will be 80 free of engagement with the curtains, the latter then being fully drawn upwardly into the top and wound upon the rollers. 85

In the modified construction shown by Figs. 7 to 10, inclusive, the same essential 90 features are shown with the difference that each fastener comprises a two-part clip, or a clip having one member or clamping jaw movable in relation to the other. This modified form of the clip comprises a 95 narrow jaw or strip 30 pivoted at its upper end, as at 31, to the inner edge of the filler board 8 and having its lower extremity bent or shaped to provide a recess or seat 32. To the lower end of the jaw 30 below the recess or seat 32 the lower end of a movable jaw 33 is loosely pivoted and is adapted to be swung laterally with relation to the main or supporting jaw 30 or drawn inwardly away from the latter at an angle, 100 as shown in dotted and full lines by Figs. 7 and 8. The upper end of the jaw or strip 33 is adapted to engage a wedge block 34 secured to the outer side edge of the lower portion of the frame 7 for the curtain assembly, the said wedge block or retainer 34 having an inclined edge 35 and a shouldered seat 36, with relation to which the upper end of the jaw or strip 33 has 105 movement. This wedge or retainer 34 holds the jaw or strip 33 in close relation to the main or supporting jaw or strip 30. The modified structure shown by Figs. 7 to 10, inclusive, has the same operation in regard 110 to holding the side edges of the adjacent 115

120 125 130 135

- curtains in overlapped relation as the first form of clip hereinbefore described, and in the operation of this modified form the jaw 33 is released and opened and the curtain 15 is then drawn downwardly close against the jaw 30 until the strip 29 in the lower edge of the curtain reaches the recess or seat 32, and the jaw will then be closed and secured by engagement with the receiver and thereby hold the curtain in lowered position. The seat 32 and the two jaws 30 and 33 will be so proportioned that they will hold both overlapped edges of the curtains firmly along the full length of said edges. In the modified form of the curtain fastener as shown by Figs. 7 to 10, inclusive, it will be observed that the lower extremities of the fastener or clip depend loosely over the side of the vehicle or automobile body and when not in use are adapted to be swung or turned upwardly into the top in the same manner as the form of clip heretofore described and be retained in the top against movement.
- Both forms of the improved device will be exceptionally effective in holding the overlapped side edge portions of curtains and retain the entire curtain organization in effective shape with tight jointures. Moreover, both forms of fasteners have a clamping action relatively to the side edge portions of the curtains engaging the same, and the recess or seat 32 at the lower end of the modified form of the clamp will serve to align the lower stiffening or reinforcing bars of the curtains between the overlapped side edge portions of the latter.
- What is claimed as new is:
1. In a curtain fastening means of the class specified, the combination with a vehicle top and body, of a curtain organization including curtains having adjacent edges, and fastening means consisting of clamping members movably secured to the top and disposed for movement of the side edge portions of the curtains therethrough to hold the latter in close joined overlapping relation.
  2. In a curtain means of the class specified, the combination with a vehicle top and body, of a curtain organization associated with the top and comprising rollers having curtains connected thereto for movement upwardly into and downwardly from the top, and fastening devices connected to portions of the top and depending down to the body and having means for receiving and firmly securing the overlapped edge portions of the curtains.
  3. In a curtain fastening means of the class specified, the combination with a vehicle top and body, of a curtain organization mounted in the top and comprising curtains and means for winding the said curtains to permit the latter to move downwardly and upwardly with relation to the top with the side edge portions of the curtains in overlapped relation, and fastening means for the overlapped edges of the curtains having clamping jaw members between which the side edge portions of the curtains are snugly held, the fastening means being movable upwardly into the vehicle top when not in use.
  4. In a curtain fastening means of the class specified, the combination with a vehicle top and body, of a curtain organization associated with the top and comprising curtains movable downwardly and upwardly with relation to the top and the vehicle body, the side edge portions of the curtains having an overlapped relation, and clamping means interposed between the top and the body and having jaws which permit the edge portions of the curtains to freely move therethrough and also operable for engaging the overlapped side edge portions of the curtains and holding the latter in tight joined relation, the said fastening means being pivoted to portions of the top and movable upwardly into and held within the top when not in use.
  5. In a curtain fastening means of the class specified, the combination with a vehicle top and body, of a curtain organization associated with the top and comprising curtains movable upwardly into and downwardly from the said top, having an overlapping side edge arrangement and fastening means extending between the top and body and having jaws which permit the side edges of the curtains to move therethrough and also operable for engaging the side edge portions of the curtains to hold the latter firmly in associated tightly joined overlapped relation, the said fastening means being always connected to and movable upwardly into and downwardly from the top.
  6. In a curtain fastening means of the class specified, the combination with a vehicle top and body, of a curtain organization associated with the top for storage in the latter when not in use and comprising curtains with the edges thereof maintained in overlapped relation, and fastening means consisting of yielding clamping jaws with relation to which the curtains are movable, the said jaws operating to hold the overlapped side edge portions of the curtains in tightly joined association.
  7. In a curtain fastening means of the class specified, the combination with a vehicle top and body, of a curtain organization associated with the top and comprising curtains movable upwardly into and downwardly from the top and having overlapped side edge portions, the curtains having stiffening devices at their lower ends, and fastening devices having opposed yield-

ing jaws through which the side edge portions of the curtains and the opposite extremities of the stiffening devices have movement, the jaws being also operable to hold the side edge portions of the curtains tightly joined, and the stiffening devices operating to separate the jaws for freedom of movement of the remaining portions of the curtains through the fastening means.

8. In a curtain fastening means of the class specified, the combination with a vehicle top and body, of a curtain organization mounted in the top and comprising curtains movable upwardly into and downwardly from the top having overlapped side edge portions, and fastening means

for the side edge portions of the curtains, the fastening means in one adjustment permitting the side edge portions of the curtains to freely move therein, said fastening means having upwardly projecting guide partitions and lower fastening extremities projecting therefrom and the upper extremities of the fastening means also being provided with pivot arms for movably connecting the said fastening means to the top to permit movement of the fastening means upwardly into and downwardly from the top.

In testimony whereof I have hereunto set my hand.

EDWARD J. THURBER.
